UNITED STATES PATENT OFFICE

2,647,871

WATER CONDITIONER

Allen W. Frazier, Glen Ellen, Calif.

Application June 1, 1949, Serial No. 96,453

1 Claim. (Cl. 210—24)

1

My present invention relates to water conditioners and more particularly to a portable conditioner for drinking water.

It is a well known fact that the composition of water differs greatly in different localities. In many localities the water is highly mineralized and discolored. In many localities water is contaminated requiring chlorine treatment which does not improve the taste for drinking purposes and sometimes impairs the transparency of the water.

In my present invention water of the character above mentioned may be passed through the conditioner by a simple connection to the house tap or any other water supply line and passed to a pitcher or other container for drinking purposes. The processed water flows from the conditioner clear and transparent. All discoloration is removed together with objectionable odors and becomes palatable.

The principal object of my invention is to produce an improved simple, inexpensive portable water conditioning device.

Another object is to produce a water conditioning device in which water to be conditioned passes uniformly down through a suitable exchange mineral body and up through a central passage and out to another container such as a pitcher etc.

Still another object is to produce a water conditioner device in which the exchange mineral body may be easily reactivated and the exchange mineral body back-washed without removal from the container.

A still further object is to produce a device of the character above indicated which may be inserted through the small neck of a container of a bottle or jug and in which the flexible outlet tube may also be used to seal the device from foreign matter or from leakage if accidentally overturned, and

Other objects comprising the construction and operation of my invention will be more apparent as the description of the same progresses.

In the drawings illustrating the preferred embodiment of the device:

Fig. 1 is a side elevation of the conditioner, the inlet tube being broken off and showing in dot-and-dash lines a funnel attachment adjusted to the end of the tube to receive reactivating salt solution.

Fig. 2 is a vertical central cross-section, portions of which are shown in elevation and other portions being broken off.

Fig. 3 is a fragmentary side elevation of the 55 of slits at 27 providing outlet openings for in-

2

upper portion of the device illustrating the method of closing the device when not in use.

Fig. 4 is an enlarged fragmentary cross-section of the upper side of the neck of the device shown in Fig. 2 but showing the relief valve in more detail, and

Fig. 5 is a fragmentary cross-section taken on the line 5—5 of Fig. 2 particularly showing the grill-end of the outlet tube.

Referring more in detail to the drawing, 10 indicates a container which is provided with a screw threaded neck 11 to which is screwed a special T fitting 12. The container is preferably constructed of glass or other transparent material giving visible access to the contents of the container at all times. The T fitting 12 may be constructed from any suitable material of a non-ferrous nature, preferably metal. The container 10 is preferably symmetrical in cross-section but may be of a different shape if desired. A quart bottle or a jug will suffice.

The T fixture 12 is provided with an inlet boss 13 which is hollow and fitted with a sweated-in nipple 14 over which is fitted a flexible rubber tube 15. The free end of the tube 15 may be adapted to fit any standard slip-over or screw fitting which will connect with a water faucet or other source of water supply. In the top of the T fitting 12 I have located a tube 16. The tube 16 is sweated or otherwise sealed at 17 in the top portion of the fitting 12 and projects above the said fitting to form another nipple 18 to which is attached an outlet flexible rubber tube 19. The outlet end of the tube 19 may be directed into any receiving container for conditioned water such as a pitcher or a jug or any handy container which can be placed in a home refrigerator for cooling etc.

Referring back to the T fitting 12, a second tube 20 is sealed at 21 in an opening in the lower portion of the T fitting 12. The tube 20 is larger than the tube 16 and provides a space 22 between the two tubes, shown in Fig. 2. The lower end of the outer tube 20 is sealed against the outside of the inner tube 16, indicated by the sleeve 23.

In the upper portion of the T fitting 12 there is provided a chamber 24 into which the inlet tube 15 connects. This chamber 24 connects with the space 22 around the two tubes 16 and 20 making one continuous chamber. In the upper portion of the chamber 24, I have provided an air vent valve 25 preferably sealed in a hollow boss 26 formed on the T fitting 12.

The outer tube 20 is provided with a plurality

coming unconditioned water, the operation of which will be described further along in the specification.

In the lower portion of the container 10 and telescoped over the tube 16 is an extension tube 28 the upper end of which is fitted with a rubber tube coupling member 29. The tube 28 is provided for the purpose of extending the central tube 16 or adjusting it higher or lower depending upon the depth of the container 10. The rubber tube coupling 29 slides on the tube 16. If preferred, the tube 16 and extension piece 28 may be composed of one piece. In either case, the bottom of the tube is pinched in, as shown in Fig. 5, and slots 30 are formed providing a grill entrance to the tube.

The lower portion of the T fixture 12 is internally threaded to engage the threaded portion 11 of the container 10, the T fixture 12 being sealed with the container 10 by means of the rubber bushing 31 which also acts as a spacer and cushion between the outer tube 20 and container neck 11 and thereby provides an air space 32 connecting with the interior of the said container. In the upper portion of the tube 20 there is provided a port 33 which communicates with the air space 32 between the container neck portion 11 and the interior of the container.

In operation, the T fixture 12 and the tubes 16 and 20 together with the relief valve 25 are assembled as a unit. The container 10 is filled with exchange mineral matter 35 to an approximate level in the container, indicated at 36. The flexible tube 15 is attached to a water supply line and water flows into the chamber 24 of the T fitting 12 and down between the tubes 16 and 20 and outwardly through the slots 27 in the tube 20 into the upper portion of the container 10 above the level 36 of the exchange mineral 35. The water passes down through the exchange mineral 35 uniformly through the whole body of the mineral matter and passes up through the slots 30 forming the grill in the end of the tube 16, and out through the outlet tube 19 to any suitable container. The port 33 permits surplus water to collect in the upper portion of the container 10, shown in Fig. 2, so that the neck portion 11 may be partially filled with water.

During the filling of the container 10 with water, the air in the container 10 is forced upwardly as the water displaces it and is manually vented through the ball valve 25. Any type of valve may be used in place of the one shown which will permit air to be released and prevent water from passing through when the valve is closed. The port 33 in the pipe 20 permits air in the upper portion of the container to escape up into the T fixture chamber 24, and be vented through the valve 25, thereby permitting the water level in the container 10 to rise above the highest slot 27 in the tube 20. This makes possible the uniform flow of water through the device without undue agitation in the upper portion of the container 10.

Sediment or other voids coming from the inlet tube 15 are trapped in the container 10 above the top of the exchange mineral matter 35 and appear as a flock like material. To clear this flock condition the rubber tubes 15 and 19 are reversed and water is forced down through the tube 16 and out through the inlet nipple 14.

When the exchange mineral matter 35 becomes deactivated from use over a period of time, it may be reactivated by placing a small funnel 40 in the end of inlet tube 15 and a quantity of

salt solution allowed to pass through the conditioner in the same manner as when attached to a water faucet. The tube 15 may be again attached to the water faucet and the salt solution run off, after which the conditioner is again ready to produce conditioned water for drinking purposes.

When the conditioner is not in use, the tube 15 may be removed from the nipple 14, and the free end of the tube 19 is then brought around and placed over the nipple 14, shown in Fig. 3. This arrangement not only prevents water from being spilled should the container be overturned but also prevents any foreign matter from entering the device when not in use, making sure that the conditioner is always in a sanitary condition.

Any suitable exchange mineral such as zeolite may be used with good results. I do not claim that this device will eliminate bacteria or similar impurities which may be in the tap water but it will remove discolorations, odors, and other foreign matter rendering the processed water clear, odorless and palatable to the taste.

While I have shown and described the preferred embodiment of my invention somewhat in detail yet it is to be understood that I may vary the shape and proportions and may substitute equivalent structure within wide latitude within the scope of the appended claim.

Having thus described my invention, what I claim as new is:

In an improved water conditioner of the portable type using a dispensable narrow necked transparent container partially filled with exchange mineral matter, a removable fixture frictionally sealed in the said container neck comprising a T like member with an internal chamber, a water inlet and an air check valve member communicating with said chamber, an exterior tube sealed in said T member at the lower side of said chamber, the lower end of said exterior tube extending downwardly into the said exchange mineral matter, ports located in said exterior tube communicating with the interior of said container and said T member chamber, an internal tube coaxially located in said exterior tube, the upper end of which is located through the top of said T member, said internal tube and external tube being provided with a passage way between said tubes, said passage way being open into the said chamber at the top of said exterior tube and closed at the bottom of said exterior tube, said internal tube extending down in said mineral exchange matter to a point adjacent the bottom of said container, the lowermost end of said internal tube being flattened and compressed together with vertical slots being formed therethrough to communicate with the interior of said internal tube.

ALLEN W. FRAZIER.
